Louis Chartoff
BY *George E. Tamm*
ATTORNEY

UNITED STATES PATENT OFFICE

LOUIS CHARTOFF, OF NEW HAVEN, CONNECTICUT

DISPLAY STAND

Application filed May 4, 1929. Serial No. 360,433.

This invention relates to a new and improved display stand.

It is the object of this invention, among other things, to provide a device of this character that will be complete, in all of its appointments, practically unlimited in the scope of its use, and provided with article holding platforms of varying sizes and shapes and relative positions, that may be independently 10 rotatable, as well as to provide a stand which will be both neat and pleasing in its appearance.

To these, and other ends, my invention consists in the display stand, having certain 15 details of construction and combinations of parts, as will be hereinafter described and more particularly pointed out in the claims.

Referring to the drawings, in which like reference characters indicate like parts in the 20 several figures;

Figure 1 is a sectional elevation of my display stand;

Figure 2 is a plan view thereof, the parts in section being taken generally upon line 25 2—2 of Figure 1; and

Figure 3 is a fragmentary view, the parts in section being taken generally upon line 3—3 of Figure 1.

In the embodiment of my invention as 30 herein disclosed 10 indicates the base, which is shown as being constructed with four arms and mounted upon casters. Secured to this base is a base plate 11, within which is threadably secured the standard 12, which is preferably hollow and provided at its upper end 35 with a thimble 13 having a raceway for the balls 14.

Telescopically fitted over the standard 12 is the sleeve member 15, somewhat shorter in 40 length than the standard 12, having at its lower end a thimble 16, within which is a raceway for the balls 17, which latter engage the cone 18 fixed to the standard 12. The upper end of the sleeve member 15 is closed 45 by a cap member 19, having an inside cone 20, which projects through and has a bearing against the balls 14, which provide an anti-friction bearing therefor. After the upper part of the sleeve member 15 has been adjusted 50 the cone 18 is positioned and an anti-

friction bearing is provided for the sleeve member.

Secured to the sleeve member 15 are a plurality of collars 21, there being a collar for each of the display platforms. Resting on 55 each of these collars is a shell 22 having a raceway therein for the balls 23, against which rides the collar 24, the upper edge of which projects above the top of the shell 22.

Encircling the sleeve member 15 and resting upon the top of the collar 24 is a platform plate 25, which supports the platform 26, and is held against upward movement by the collar 27.

In the drawings I have shown three platforms, the upper and lower ones being substantially flat but of different diameters, but a greater or less number may be used as desired.

The intermediate platform is provided 70 with a flaring or inclined wall 30, which terminates at its lower end in a flange or band 28, which may be of any desired shape, that provides a support for any article placed against the flaring or inclined wall 30, such 75 as a basket, box or the like.

By means of a pulley 29 fixed to the sleeve member 15, the latter and the display platform associated therewith, may be rotated by means of a belt or the like.

There are minor changes and alterations 80 that may be made within my invention, aside from those herein suggested, and I would therefore have it understood, that I do not limit myself to the exact construction herein 85 shown and described, but claim all that falls fairly within the spirit and scope of the appended claims.

Having described my invention, what I 90 claim as new and desire to secure by Letters Patent, is:

1. In a display stand; a base; a hollow standard secured thereto; a thimble in the upper end of the standard; a sleeve outside of and shorter than the standard; a cap closing the upper end of the sleeve having an inside cone that projects into the thimble; a plurality of balls between the thimble and cone providing an anti-friction bearing therebetween; a thimble at the lower end of 100

the sleeve; an adjustable collar on the standard; and a plurality of balls between the collar and last mentioned thimble, whereby an anti-friction bearing is provided at the 5 lower end of the sleeve.

2. In a display stand; a base; a hollow standard secured thereto; a thimble in the upper end of the standard; a sleeve outside of and shorter than the standard; a cap closing the upper end of the sleeve having an inside cone that projects into the thimble; a plurality of balls between the thimble and cone providing an anti-friction bearing therebetween; a thimble at the lower end of the sleeve; an adjustable collar on the standard; a plurality of balls between the collar and last mentioned thimble, whereby an anti-friction bearing is provided at the lower end 10 of the sleeve; and a plurality of platforms 15 associated with the sleeve adjustable relatively thereto.

3. The combination in a display stand; of a base; a hollow standard secured thereto; a thimble in the upper end of the standard; a 25 sleeve outside of and shorter than the standard; a cap having an inside cone that projects into the thimble forming both a closure for the upper end of the sleeve and a bearing therefor; a plurality of balls between the 30 thimble and cap forming an anti-friction bearing therebetween; a thimble at the lower end of the sleeve; an adjustable collar on the standard; a plurality of balls between the collar and last mentioned thimble whereby an 35 anti-friction bearing is provided at the lower end of the sleeve; a plurality of collars adjustably secured on the sleeve; a shell resting on each of said collars; a ring collar, encircling the sleeve above the first mentioned 40 collar, and within the shell; a plurality of balls between the shell and the ring collar; and a platform encircling the sleeve and supported by the ring collar.

4. The combination in a display stand; of a base; a hollow standard secured thereto; a thimble in the upper end of the standard; a 45 sleeve outside of and shorter than the standard; a cap having an inside cone that projects into the thimble forming both a closure for the upper end of the sleeve and a bearing therefor; a plurality of balls between the thimble and cap forming an anti-friction bearing therebetween; a thimble at the lower 50 end of the sleeve; an adjustable collar on the standard; a plurality of balls between the collar and last mentioned thimble whereby an anti-friction bearing is provided at the lower end of the sleeve; a plurality of collars adjustably secured on the sleeve; a shell resting on each of said collars; a ring collar, encircling the sleeve above the first mentioned 55 collar, and within the shell, that projects above the top thereof; a plurality of balls between the shell and the ring collars; and a 60

platform encircling the sleeve and supported by the ring collar.

In testimony whereof, I have hereunto affixed my signature.

LOUIS CHARTOFF.
